US0D1019572S

(12) **United States Design Patent** (10) **Patent No.:** **US D1,019,572 S**
(45) **Date of Patent:** **** Mar. 26, 2024**

(54) **CONNECTOR**

(71) Applicant: **DONGGUAN YUANCHUANG ELECTRONIC TECHNOLOGY CO., LTD.**, DongGuan (CN)

(72) Inventor: **HongPing Tan**, DongGuan (CN)

(73) Assignee: **DONGGUAN YUANCHUANG ELECTRONIC TECHNOLOGY CO., LTD.**, Dongguan (CN)

(**) Term: **15 Years**

(21) Appl. No.: **29/831,010**

(22) Filed: **Mar. 16, 2022**

(51) **LOC (14) Cl.** **13-03**

(52) **U.S. Cl.** USPC **D13/147**

(58) **Field of Classification Search**

(57) **CLAIM**

I claim the ornamental design for a connector, as shown and described.

DESCRIPTION

FIG. 1 is a perspective view of a connector showing my new design.

FIG. 2 is a second perspective view of FIG. 1, viewed in another aspect.

FIG. 3 is a front view thereof.

FIG. 4 is a back view thereof.

FIG. 5 is a left view thereof.

FIG. 6 is a right view thereof.

FIG. 7 is a top view thereof.

FIG. 8 is a bottom view thereof.

FIG. 9 is a perspective view thereof, shown in one possible environment;

FIG. 10 is a perspective view thereof, shown in a second possible environment;

FIG. 11 is a perspective view thereof, shown in a third possible environment;

FIG. 12 is a perspective view thereof, shown in a fourth possible environment;

FIG. 13 is a perspective view thereof, shown in a fifth possible environment; and,

FIG. 14 is a perspective view thereof, shown in a sixth possible environment.

The broken lines in the drawings depict portions of the connector that form no part of the claimed design.

1 Claim, 14 Drawing Sheets
